Attorney

UNITED STATES PATENT OFFICE.

OTIS ALLEN KENYON, OF NEW YORK, N. Y.

AUTOMATIC WELDER.

Application filed December 18, 1920. Serial No. 430,408.

To all whom it may concern:

Be it known that I, OTIS A. KENYON, a citizen of the United States, residing at New York city, in the county of New York and State of New York, have invented certain new and useful Improvements in Automatic Welders, of which the following is a specification.

My invention relates to automatic electric arc welding, and especially to an improvement in the feeding devices which feed the electrode towards the work. In automatic arc welding it is necessary to use an electrode, either wire or strip, that is straight and free from kinks. Bends in the electrode cause the path of the arc to wobble and kinks cause excessive friction in the drive. There are automatic arc welders of the motor-driven type that include a set of standard straightening rolls driven by the feeding roll, but this arrangement is undesirable in any case and totally impracticable when very large size electrodes are used.

In order to give the best results it is essential that the motor which feeds the electrode to the work, should have no other utility than to control the feeding speed of the electrode towards the work, as all other operations which are put upon this motor disturb both the motor speed and the stability of the arc. I have devised an improvement whereby any size electrode can be used from a reel without imposing any load on the feeding motor. In fact I have provided a device which will reduce by a considerable amount the usual and necessary load heretofore placed on the feeding motor.

My invention consists in using an auxiliary motor for driving the straightening rolls, and controlling the speed of said motor by the flexure in the electrode between the straightening rolls and the feeding rolls.

Without confining myself to any particular construction, I show in—

Fig. 1 a general assembly and electrical connections for a mechanism which illustrates the principle of my invention.

Fig. 2 is a detail of the circuit controlling device shown at 7' in Fig. 1.

Referring to the drawings the electrode 1 is unwound from a reel 4 and fed to-

wards the work, which I have indicated by the numeral 2. 3—3 are the usual feeding rolls actuated by an electric motor for the purpose of feeding the electrode towards the work. 5—5' are straightening rolls of a well-known type which are adapted to straighten the electrode as it comes from the reel and present the same to the feeding rolls 3 in substantially straight form. The straightening rolls are adjustably journaled in a suitable framework 5^a and the rolls 5—5' have their axes at right angles to each other, so that the rolls 5 straighten in one direction and the rolls 5' in the other, thereby insuring equal straightening pressure for the purpose of removing kinks and bends in either direction.

Mounted on a suitable base I provide an electric motor 6, which rotates a shaft 6' 70 on which the knurled feeding roll 7 is mounted. Opposed to the feeding roll 7 is a corresponding roll, preferably slotted, which acts as an idler roll in cooperation with the knurled roll 7 in feeding the electrode at this point. The motor 6 is connected to a source of constant-potential 6^a, and its speed is adjusted by the field rheostat 13, to a value higher than the maximum feeding speed of the feeding roll 3—3. 75

I will now describe the circuit controlling device which I have devised to control the speed of the motor 6 and reference is made to the Fig. 2 of the drawings. A plate 7' is provided supported by any suitable 80 means, and this plate has a slot 7^a through its center, through which slot the electrode 1 passes. A plunger 8 having a head 8^a, and backed by a spring 10 is mounted within the slot 7^a adjacent the path of the electrode. The opposite end of this plunger is in proximity to the contacts 9—9^a, and is adapted when moved towards said contacts against the tension of the spring 10, to force said contacts together and close a circuit at 95 this point. The contacts 9—9^a are connected through the lines 12—12' across the terminals of the field rheostat, and are adapted to short circuit said rheostat when united.

The operation of my arrangement is as 100 follows:

The electrode is drawn from the reel 4

- by the pull of the roll 7, actuated by the motor 6, and the electrode is drawn through the straightening rolls 5, 5'. The feeding rolls 3-3 are rotating and are feeding the electrode at that time towards the work. Since the motor 6, as has been heretofore described, is normally operating at a higher speed than the electric motor which is actuating the feed rolls 3-3, the electrode will be fed faster through the rolls 7, than through the rolls 3-3, and will flex between said points due to this difference in speed. When the electrode becomes so flexed between these points that it bears against the head 8^a of the plunger 8, it will actuate said plunger against the tension of the spring 10, and close the contacts 9-9^a, thereby short circuiting the rheostat 13, and reducing the speed of the motor 6. Upon the reduction of the speed of the motor 6, below the speed of the motor driving the feeding rolls, the electrode will be fed by the rolls 3 at a faster rate than by the roll 7, and the flex in the electrode between these points will be reduced. As soon as the flex between these points is reduced so that the electrode ceases to bear upon the plunger 8, the contacts 9-9^a will be opened, and the motor 6 will resume its normal speed. The electrode is normally flexed between the rolls 3 and the rolls 7 just enough to keep it in the same direction and to eliminate any possibility of a direct pull from the feeding rolls 3 against the straightening rolls, which would impose an excessive load on the feeding motor driving the rolls 3 and defeat the purpose of the device.
- In the operation of my arrangement the motor 6 it will be seen, runs alternately too fast and too slow in comparison with the motor driving the feeding rolls 3-3, and the average of the speed of the motor 6 is always just equal to the feeding speed required to keep the arch at constant length. No mechanism is shown for the driving of the feeding roll 3-3 and they may be driven by a motor controlled by the arc or by any other suitable means, either continuous or step by step.
- It will thus be seen that I have devised an arrangement for an automatic welder that will relieve the strain upon the feeding motor, to a greater extent than has been heretofore possible, and that by my arrangement the electrode itself controls the speed of the straightening rolls, and the feed of the electrode through these rolls, from the reel on which it is wound.
- Having thus described my invention what I claim as new and desire to secure by Letters Patent is:-
1. In automatic arc welding, mechanism for feeding the electrode toward the work, and means for reducing the load or pull on the feeding motor.
  2. In automatic arc welding, mechanism for feeding the electrode toward the work, and adjustable means for reducing the load or pull on the feeding motor.
  3. In automatic arc welding, mechanism for feeding the electrode toward the work, and means for flexing the said electrode as it nears the said feeding mechanism, for the purpose of reducing the load or pull on the feeding motor.
  4. In automatic arch welding, mechanism for feeding the electrode toward the work, and separate means for delivering the said electrode to the said feeding mechanism, said means being controlled by the speed of the feeding motor.
  5. In automatic arch welding, mechanism for feeding the electrode toward the work, and separate means for delivering the said electrode to the said feeding mechanism, said means being controlled by the speed of the feeding motor and adapted to reduce the load on the said feeding motor.
  6. In automatic arch welding, mechanism for feeding the electrode toward the work, and separate means for delivering the said electrode to the said feeding mechanism, said means being adapted by the speed of the feeding motor and adapted to flex the electrode as it nears the feeding mechanism.
  7. In automatic arc welding, mechanism for feeding the electrode toward the work, and separate means for delivering the said electrode to the said feeding mechanism, said means being adapted to flex the electrode as it nears the feeding mechanism and to limit the amount of flexure thereof.
  8. In automatic arch welding, mechanism for feeding the electrode toward the work, and separate means for delivering the said electrode to the said feeding mechanism, said means being adapted to intermittently run faster than the feeding mechanism to flex the electrode as it nears the feeding mechanism.
  9. In automatic arc welding, mechanism for feeding the electrode toward the work, and separate means for delivering the said electrode to the said feeding mechanism, said means being adapted to run alternately faster and slower than the feeding mechanism, to flex the electrode.
  10. In automatic arc welding, mechanism for feeding the electrode toward the work, and separate means for delivering the said electrode to the said feeding mechanism, said means being controlled by the speed of the feeding mechanism and adapted to be run alternately faster and slower to maintain the electrode in a flexed state as it nears the feeding mechanism.
  11. In automatic arc welding, means for unwinding from a reel and straightening an electrode, mechanism for feeding said electrode toward the work, and means for controlling the speed of the said straightening

means by the speed of the said feeding mechanism.

12. In automatic arc welding, means for unwinding from a reel and straightening an electrode, separate mechanism for feeding said electrode toward the work, said means adapted to be controlled by the feed-

ing mechanism to run alternately faster and slower, to maintain the electrode flexed as it enters the feeding mechanism.

10

In testimony whereof I hereunto affix my signature.

OTIS ALLEN KENYON.
